CIGAR LIGHTER OR SIMILAR ARTICLE

Harold F. Sitterle, Somers, N. Y., assignor to Ronson Corporation, Newark, N. J., a corporation of New Jersey

Application August 10, 1954, Serial No. 31,808

Term of patent 14 years

(Cl. D48—27)

To all whom it may concern:

Be it known that I, Harold F. Sitterle, a citizen of the United States of America, residing in Somers, in the county of Westchester and State of New York, have invented a new, original, and ornamental Design for a Cigar Lighter or Similar Article, of which the following is a specification, reference being had to the accompanying drawing, forming part thereof in which:

Fig. 1 is a perspective view of a cigar lighter, showing my new design;

Fig. 2 is a front elevational view thereof; and

Fig. 3 is a top plan view.

The dominant features of my design are shown in solid lines.

I claim:

The ornamental design for a cigar lighter or similar article, substantially as shown and described.
